US00D888709S

(12) **United States Design Patent** (10) **Patent No.:** **US D888,709 S**
(45) **Date of Patent:** **** Jun. 30, 2020**

(54) **ELECTRONIC COMPUTER**

(71) Applicant: **Toshiba Client Solutions CO., LTD.**,
Tokyo (JP)

(72) Inventor: **ChingTing Kang**, Tokyo (JP)

(73) Assignee: **Toshiba Client Solutions CO., LTD.**,
Tokyo (JP)

(**) Term: **15 Years**

(21) Appl. No.: **29/660,876**

(22) Filed: **Aug. 23, 2018**

(30) **Foreign Application Priority Data**

May 28, 2018 (JP) 2018-011551

(51) **LOC (12) Cl.** **14-02**

(57) **CLAIM**

The ornamental design for an electronic computer, as shown and described.

DESCRIPTION

FIG. 1 is a perspective view of an electronic computer showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left side elevational view thereof;

FIG. 9 is a right side elevational view thereof;

FIG. 10 is a perspective view of the electronic computer of FIG. 1 shown in a closed-position;

FIG. 11 is another perspective view thereof;

FIG. 12 is a front elevational view thereof;

FIG. 13 is a top plan view thereof;

FIG. 14 is a right side elevational view thereof;

FIG. 15 is a perspective view of the electronic computer of FIG. 1 shown in an alternate configuration where the tablet and keyboard portions are separate;

FIG. 16 is another perspective view thereof;

FIG. 17 is a front elevational view of the tablet portion of the electronic computer, shown separated from the keyboard portion for clarity of illustration;

FIG. 18 is a rear elevational view; and,

FIG. 19 is a top plan view of the keyboard portion of the electronic computer, shown separated from the tablet portion for clarity of illustration.

1 Claim, 15 Drawing Sheets
